(57) CLAIM

The ornamental design for a hand drum, as shown and described.

DESCRIPTION

FIG. 1 is a top plan view of a hand drum showing my new design;

FIG. 2 is a bottom plan view thereof;

FIG. 3 is a front elevation view thereof, the undisclosed rear, left and right side views being the same; and,

FIG. 4 is a perspective view thereof.

The broken lines shown in FIG. 2 represent the portion of the design which forms no part of the claim.

1 Claim, 4 Drawing Sheets
